DESIGN FOR A GUIDE FOR ELECTRICAL CONDUCTOR OR THE LIKE

Hazel Watson, Detroit, Mich.

Application October 14, 1947, Serial No. 141,898

Term of patent 14 years

(Cl. D26—1)

To all whom it may concern:

Be it known that I, Hazel Watson, a citizen of the United States of America, residing at Detroit, in the county of Wayne and State of Michigan, have invented a new, original, and ornamental Design for a Guide for Electrical Conductor or the like, of which the following is a specification, reference being had therein to the accompanying drawing, forming a part thereof, wherein:

Fig. 1 is a front elevational view of a guide for electrical conductor or the like, showing my new design;

Fig. 2 is a side elevational view thereof; and
Fig. 3 is a top plan view thereof.

I claim:

The ornamental design for a guide for electrical conductor or the like, substantially as shown.
HAZEL WATSON.
